P. LEO.
 PAPER GUIDE FOR SEAL PRESSES,
 APPLICATION FILED JULY 11, 1917.
 1,257,717.
 Patented Feb. 26, 1918.

INVENTOR
Paul Leo,
 BY *J. Parker*
 ATTORNEY

UNITED STATES PATENT OFFICE.

PAUL LEO, OF ELIZABETH, NEW JERSEY.

PAPER-GUIDE FOR SEAL-PRESSES.

1,257,717.

Specification of Letters Patent. Patented Feb. 26, 1918.

Application filed July 11, 1917. Serial No. 179,970.

To all whom it may concern:

Be it known that I, PAUL LEO, a citizen of the United States, and resident of Elizabeth, in the county of Union and State of New Jersey, have invented certain new and useful Improvements in Paper-Guides for Seal-Presses, of which the following is a specification.

This invention relates to seal presses and the like, and my improvements comprise novel and convenient means for guiding the sheets to be impressed between the die members of a press. My present invention is particularly adapted for use with the foot controlled press such as is shown in my U. S. Patent No. 1,228,934, and is illustrated in the accompanying drawing in which,

Fig. 1 is a plan view of the paper guides and the adjustable mechanism therefor; and

Fig. 2 is a side elevation of the same.

In carrying out my invention I employ a table, as *a*, upon which one die member *b* of a seal press is seen to be mounted. Said die member *b* may be carried by a usual form of hand press *c*, whose hang-over portion, represented in cross section at *c'* in Fig. 1, carries the upper die member (not shown). An L-shaped bracket *d*, having slot *d'*, with thumb screw *d''*, to adjustably secure it to table *a*, has a V-shaped gripping surface on its angular arm *d''* to coöperate with an oppositely disposed gripping member *e*, to engage and hold the press *c* between them.

A bracket *f* which is of substantially U-shape, with the upper member *f'* and lower member *f''*, is adjustably supported upon the table *a* in the following manner. An angle piece *g* fits between one side of bracket *f* and the upper surface of a member *h*, which latter is secured, as by screws *h'*, to the table *a*. Said member *h* has a slot *h''* to receive a thumb screw *i*, by which it is adjustably secured to the table; and said bracket *f* has a slot *f''* in which a thumb screw *h''* may adjustably secure said bracket to said angle piece.

Also the angle piece *g* has a slot *g'*, crossing the slot *h''* in member *h*, the thumb screw *i* also engaging said slot *g'* where the angle piece *g* intersects the member *h*. Thus, by loosening the thumb screw *i* the angle piece *g* is capable of universal movement in a

horizontal plane, for a purpose to be described hereinafter.

The bracket member *f'* is shown as having an offset *f''*, with a vertical slot *f''*, in which is adjustably contained a stem *f''* that is fast to an upper paper guide *j*, which is thereby supported in position above a lower paper guide *k*, the latter being secured to and supported by the bracket member *f''*.

Thus the bracket members *f'*, *f''*, respectively support the upper and lower paper guides in opposed relation, said paper guides, as a pair, being unitedly adjustable, through the universal movement of the bracket aforesaid, whereby said paper guides may be brought into operative relation with respect to the die members. Also, the upper guide *j*, through its vertical movable stem *f''* is adjustable as to height, to vary the space separating it from guide *k*, and a set screw *l* serves to secure it in the desired position.

The guide *j* is shaped like the section of a cone, having an upwardly and outwardly flaring surface, whereby it may conveniently engage and guide a sheet, to be impressed, between the guides *j* and *k* and thus between the die members. The leading edge of the guide *k* is also beveled, for the same purpose.

I claim:—

A paper guide for seal presses, the same comprising a pair of separated members for the reception of a sheet to be impressed, a U-shaped supporting bracket whose arms respectively support said members, an angle bar having a slotted upright member and a thumb screw to engage said bracket through said slotted upright member for vertical adjustment of said bracket, together with a horizontal member of said angle bar having a longitudinal slot, and a transversely disposed slotted member engaged therewith by a thumb screw, whereby said bracket is capable of universal adjustment in a horizontal plane.

Signed at 60 Broadway in the county of New York and State of New York this 23rd day of June A. D. 1917.

PAUL LEO.
